UNITED STATES PATENT OFFICE

2,311,361

PANEL CONSTRUCTION

Forrest F. Beil, Clinton, Iowa, assignor to Curtis Companies Incorporated, Clinton, Iowa, a corporation of Iowa

Application May 26, 1941, Serial No. 395,267

7 Claims.

(Cl. 20—35)

My invention relates to a construction for a woodwork panel, such as may be used for cupboard doors and the like.

The principal object of my invention is to provide a panel which when fitted in an opening will not give trouble due to shrinking and swelling.

In many part of the country the variations in atmospheric humidity are of such degree that the ordinary type of cupboard door, for example, gives very unsatisfactory performance. When the humidity is high, the door swells and sticks annoyingly in the cupboard or cabinet opening; when the humidity is low, the door may shrink so much that the catches or locks do not engage properly to keep it closed.

It is an object of my invention, therefore, to provide a construction for a panel which may be fitted into an opening as a door, for example, with assurance that shrinkage and swelling will not interfere with its satisfactory operation.

A further object is the provision of a panel construction in which the elements employed readily permit a raised central portion, in conformity with currently popular designs in stove fronts and refrigerator doors.

In a modified form of my invention it is an object to provide a door construction in which the front surface is composed of a single or built-up integral piece, concealing all joints at which relative sliding movement takes place.

A further object is to provide a construction for a panel as used in a cupboard door or the like, which can be manufactured as easily and economically as the conventional types now on the market.

With these and other objects in view, my invention consists in the construction, arrangement and combination of the various parts of my device whereby the objects contemplated are attained, as hereinafter more fully set forth, pointed out in my claims and illustrated in the accompanying drawings, in which:

Figure 1 is an elevational view of the front surface of a panel embodying my invention.

Figure 2 is an enlarged fragmentary detail view of the upper left corner of Figure 1, parts being broken away and shown in section.

Figure 3 is a vertical sectional view taken on the line 3—3 of Figure 2.

Figure 4 is a horizontal sectional view taken on the line 4—4 of Figure 2.

Figure 5 is a perspective view of the joint at a corner of the panel, from the rear, parts being broken away.

Figure 6 is an enlarged fragmentary horizontal sectional view taken on the line 6—6 of Figure 1.

Figure 7 is a view similar to Figure 6, showing a modified construction.

Figure 8 is a vertical sectional view taken on the line 8—8 of Figure 7.

Figure 9 is an elevational view of the front surface of a panel embodying a further modified form of my invention.

Figure 10 is an enlarged fragmentary detail view of the upper left corner of Figure 9.

Figure 11 is an enlarged fragmentary vertical sectional view taken on the line 11—11 of Figure 9.

Figure 12 is a horizontal sectional view taken on the line 12—12 of Figure 10.

Figure 13 is an enlarged fragmentary horizontal sectional view taken on the line 13—13 of Figure 9.

In the accompanying drawings I have used the reference numeral 20 to designate the stiles of a panel assembly. These stiles are connected together at their ends by rails 22. The rails and stiles are joined in a well known manner by a tenon 24 on the rail and a mortise 26 in the stile. Each of the stiles is provided with a rabbet 28 along its inner edge, and may have a lip portion 30 along its outer edge to overlap the adjacent portions of a cupboard or cabinet structure 32. The ends of the stiles 22 adjacent the tenon 24 may be formed with a projecting portion 34 which fits into the groove 28, and it should be noted also that the tenon 24 is preferably formed so that the planes of its major surfaces are coincident with the walls of the grooves 28, so that the tenon 24 as well as the projection 34 lies in the groove 28. A central panel 36 is provided along its edges with a tongue 38 which fits into the groove 28. The panel 36 is a fabricated slab composed of strips of wood glued together, with the grain running perpendicular to the stiles 20 and parallel to the rails 22.

45 A groove 40 is formed in the end rails 22, and the inner edges of these rails are rabbeted as at 42, leaving a lip 44 which overhangs the central panel 36. A wide groove 46 is formed in the panel 36, and the portion of the rail 22 which is continued as the tenon 24 fits into this groove. A rib 48 on the panel 36 projects into the groove 40 in the rail 22, and the remaining outward portion of the panel 36 is cut down to the same level as the groove 46, leaving an outwardly projecting lip 50. The lip 50, as may be seen in Figure 3,

overlaps the adjacent portions 32 of a cabinet or cupboard along the top and bottom of the panel, in the same way as does the lip 30 (shown in Figure 6), along the sides of the panel.

The ends of the rib 48 have a projection 49 which fits into the groove 28, for purposes later to be described.

The width of the rib 48 is somewhat less than that of the groove 40. The joint between the tongue 38 and the groove 28 is not glued, and therefore the panel 36 may slide longitudinally of the stiles. Figure 5 shows the panel 36 in its extreme lowest position relative to the rail 22, the rib 48 on the panel 36 being abutted against the lower side of the groove 40. The lip 44 is made of such width that in this extreme position it will still overlap the full thickness portions of the panel 36, so that the groove 46 is not exposed.

It may be well to point out here that ordinary woods do not swell or shrink appreciably in the direction of the grain, but the swelling and shrinkage in response to varying humidity occurs almost exclusively in directions across the grain. The panel 36, therefore, may swell considerably in a vertical direction, as viewed in Figure 1, but hardly any in the horizontal direction. In actual practice, the panel 36 is fastened to the stiles 20 by pins 52 (indicated in Figure 1), midway between the ends. Hence the panel will swell both ways from the middle. The end portions can slide in the grooves 28, and there is no direct connection to the rails 22 to interfere with such sliding movement. The extra space allowed for the rib 48 in the groove 40 is proportioned to allow the maximum sliding movement which may be expected under conditions to be encountered. Similarly, the space under the lip 44 is so proportioned.

The surfaces of the complete panel which must fit in the opening of the cupboard or cabinet are indicated at 54 in Figure 3 and at 56 in Figure 6. It will be noted that so far as these surfaces are concerned, the only shrink or swell which will affect them is in the transverse width of the two stile members which abut against the ends of the rails. These dimensions are a relatively small proportion of the entire width of the panel, so that the overall shrinkage or swelling in width will be minimized.

The greatest variation, of course, takes place in the vertical dimension of the panel 36, but if this panel swells it simply slides in such a manner that the lip portions 50 extend to a greater degree and hence further overlap the adjacent cabinet structure 32. This has no effect, of course, upon the fit of the panel in the cabinet opening.

If the complete panel assembly is mounted in the form of a door in the cabinet opening, it may be constructed with moderate clearances, with assurance that it will not stick in the opening when it swells, nor will it shrink so much that the latches or catches will fail to engage properly.

By forming the abutting edges of the stiles 20 and the panel 36 in a groove such as indicated at 58 in Figures 4 and 6, the crack which must necessarily take place in the paint film when shrinkage or swelling occurs is made as inconspicuous as possible.

The portion of the panel 36 in which the groove 46 is formed is necessarily much thinner than the central parts and the projection 49, fitting into the groove 28, thus has a useful function in overcoming any tendency of the ends of the panel 36

to curl up away from the rails 22. Similarly, the projection 34 on the rails, which also fits into the groove 28, aids in keeping the rails in line, and in overcoming any curling tendency in the relatively thin portion where the groove 40 is formed.

In the sectional views of Figures 3-6, the outer surface of the panel 36 is shown as lying in the same plane with the outer surfaces of the stiles 20. It will be apparent, of course, that the central panel may if desired project further, to give the relief effect currently popular in stove fronts and refrigerator doors. A modification of this kind is illustrated in Figures 7 and 8. In this form there is a joint 60 along which relative sliding movement of the panel 36 and the stile 20 will take place.

As illustrating the relative movement between the central panel and the rail, Figure 8 may be compared with Figure 3, since Figure 3 shows the relation of the panel 36 and the rail 32 when the panel is shrunk to the extreme position, whereas Figure 8 shows the relative position of these parts when the panel has swelled to some degree—approximately half of the total possible amount.

As has been pointed out, in the Figures 1-6 form there is relative movement between the central panel and stile along the line 58, and in the Figures 7-8 form there is relative movement along the line 60, and in each case the movement will result in a break in the paint film. This break is relatively inconspicuous and ordinarily not objectionable, but I have devised a further modified form of panel assembly wherein the relative movement takes place along lines which are concealed, so that the face of the panel will be unbroken.

This further modified form is shown in Figures 9-13. In these figures it will be seen that the rails and stiles are assembled with the customary mortise and tenon joints as indicated in Figure 12. The vertical edges of the central panel 36a, as viewed in Figure 9, are rabbeted out to leave a beveled, overhanging tongue 64 which interlocks with the tongue 62 on the stile to retain the parts in slidable engagement. Across the top and bottom of the panel 36a the back side is also rabbeted out as indicated at 66 in Figure 11, leaving a space 68 for expansion, the space being closed by a rib 70 extending from the rail 22a.

As in the forms previously described, the central panel may be fixed to the stiles midway of their length, so that it will expand and contract both ways from the middle. In this construction the front surface of the panel 36a is unbroken by any sliding joints. The construction still has the advantage of the other forms, however, in that the expansion and contraction between the outer surfaces of the rails and stiles is minimized and the only substantial result of swelling of the wood is that the edge of the panel 36a will project further beyond the rib 70, as indicated in Figure 11. This does not adversely affect the appearance or attractiveness of the panel in any way or affect its operation when used as a door.

With the interlocking tongue joint of the panel on the stiles, sliding movement may take place, but the stile serves to aid in keeping the panel flat if there is any tendency to curl. The particular form of beveled tongue and groove shown is not essential, of course, but any form of joint which will retain the central panel and still permit it to swell relative to the stiles, might be used.

Cabinets containing door panels made according to the modes herein set forth have been subjected to extreme variations in temperature and humidity, and careful examination has adequately demonstrated the consistently satisfactory performance which is obtained.

It will be seen, therefore, that my invention represents a substantial step in the way of providing a wood panel in which the disadvantages of shrinkage and swelling are overcome or minimized. Furthermore, this result has been accomplished in a structure which is attractive and neat in appearance. The structure can be manufactured as easily and economically as the conventional types now on the market.

Some changes may be made in the construction and arrangement of the parts of my device without departing from the real spirit and purpose of my invention, and it is my intension to cover by my claims, any modified forms of structure or use of mechanical equivalents, which may be reasonably included within their scope.

I claim as my invention:

1. In a panel door assembly, a central member composed of wood with the grain running transversely of the member, said member having outwardly extending tongues along its longitudinal edges, and a frame consisting of longitudinally extending stiles connected by transversely extending end rails, said stiles having grooves in their inner faces receiving the tongues on said central member, said central member being fixed against sliding movement in said grooves at laterally opposite points intermediate the ends of said stiles, but being otherwise free to slide therein in swelling or shrinking.

2. A cabinet door having vertical stiles, end rails connecting said stiles, a wood panel having a tongue and groove engagement with said stiles, said panel being fixed to said stiles at opposite points intermediate the ends of said stiles, the grain in said panel extending horizontally, lips on the outer edges of said stiles extending beyond the cabinet opening when said door is mounted therein, and end portions at top and bottom of said panel overlapping said rails and extending therebeyond to form lips at the top and bottom edges of the door.

3. A cabinet door including a rectangular frame, the side members thereof carrying longitudinal guideways, and a panel member covering said frame and retained in engagement with said side members by portions on said panel member interfitting in said guideways, said panel member having portions overlapping each side of said frame and extending beyond the cabinet opening when the door is mounted therein, the grain in said panel running perpendicular to said side members and the extent of overlap beyond the end members of said frame depending upon the swelling and shrinkage of the panel.

4. In a panel door assembly, a rectangular frame, the side members thereof having longitudinally extending grooves on their inner edges, a

channel cut longitudinally in the face of one of the end members of said frame, and a panel member slidably engaged in said grooves, and having a transversely extending rib received in said channel, said rib having projections at its ends extending into said grooves.

5. In a door assembly, a frame consisting of stiles having longitudinally extending grooves on their inner edges, mortises adjacent the ends 10 of said stiles formed as deepened portions of said grooves, a rail connecting said stiles, said rail having tenons extending into said mortises, projections at the ends of said rail adjacent the outer edge thereof, extending into said grooves, 15 a channel cut longitudinally in the face of said rail intermediate between said tenons and said projections, and a wood panel having tongues on each side engaging said grooves, the grain in said panel extending parallel to said rail, said panel overlapping said rail and having a transversely 20 extending rib interfitting in said channel in said rail, said rib being narrower than said channel, so that said panel may have limited movement in said grooves.

6. A door assembly including a frame having stiles with longitudinally extending grooves on their inner edges, said stiles having mortises adjacent their ends, end rails connecting said stiles, and a wood panel having tongues on each side 25 engaging said grooves, the grain in said panel extending parallel to said rails, said panel overlying each of said rails, each of said rails in the face thereof against the panel having a wide channel near the outer edge and a rabbet in the inner edge, the full thickness portion of the rail between the channel and the rabbet being continued at each end as a tenon extending into the mortise of the adjacent stile, and the full thickness portion between the channel and the 30 outer edge constituting a rib which is continued at each end as a projection extending into the groove of the stile, said panel in the part adjacent said rail having a wide edge rabbet and a wide groove parallel to said rabbet and spaced therefrom by a full thickness portion forming a panel 35 rib, said panel rib being continued at each end as a projection extending into the groove of the stile, the rib on said rail fitting into the rabbet on said panel, the rib on said panel fitting into the channel in said rail, and the full thickness portion of the rail between the channel and the 40 rabbet fitting into the groove in the panel.

7. A door assembly including a rectangular frame, and a panel covering said frame and extending therebeyond on each end, said panel being fixed to the side members of said frame at points intermediate the ends of said members but being otherwise slidably retained against said members, at each end edge of said panel a rabbet on the side adjacent the cross member of said frame, and a rib on the frame extending into said rabbet.

FORREST F. BEIL.
